UNITED STATES PATENT OFFICE.

THOMAS STOBS, OF MAYWOOD, ILLINOIS.

SAFETY ATTACHMENT.

1,257,148.

Specification of Letters Patent. Patented Feb. 19, 1918.

Application filed April 14, 1916. Serial No. 91,015.

To all whom it may concern:

Be it known that I, THOMAS STOBS, a citizen of the United States, and a resident of Maywood, in the county of Cook and State 5 of Illinois, have invented certain new and useful Improvements in Safety Attachments; and I do hereby declare that the following is a full, clear, and exact description thereof, reference being had to the accompanying drawings, and to the letters of reference marked thereon, which form a part of this specification.

This invention relates to improvements in safety attachments more especially intended 15 for intermittently operating machines such as die presses, punch presses, paper cutters, drop forging machines, and the like and consists of the matters hereinafter described and more particularly pointed out in the 20 appended claims.

The safety attachment is of the kind which generally includes two arms or handles, that are required to be manipulated in order to operatively connect the press to its 25 power driving member so that both hands are necessary to cause the press to operate. With both hands engaged, it is impossible for the operator to get either hand caught in the press.

30 The present invention is directed to a novel and improved form of this sort of safety attachment. One of the primary objects of the device in the embodiment of the invention shown here, is to make it impossible for the workman to start the machine without using the safety appliance exactly as it is designed to be used. The attachment is thus made "foolproof," so to speak, and the operator cannot employ other means 35 than his two hands to manipulate the safety attachment. This and other advantages will appear as I proceed with my specification.

Referring now to the drawings:

Figure 1 is a view representing a side 45 elevation of the press provided with my improved safety attachment, the elevation being as looked at from the right hand side of the press.

Fig. 2 is a view representing a front elevation of the press.

Fig. 3 is a view representing a side elevation of the press as it appears when viewed from the left side.

Fig. 4 is a view representing a transverse 50 section through the press in a plane indicated by the line 4-4 of Fig. 1.

Figs. 5, 6 and 7 are detail, side elevational views of the safety attachment with the press omitted, the several views showing the parts in the successive positions which 60 they occupy when the attachment is operated.

Referring now to that embodiment of my invention illustrated in the drawings:—10 indicates a machine of the kind described 65 of any usual construction. The press in this case is the familiar die or punch press. The press shown is of the kind having a tilting bed and comprises a fixed base 11 and a tilting body 12, which may be swung 70 upon the base in a familiar manner to incline the bed plate 13. 14 indicates the plunger, which is operatively connected to a shaft 15, adapted to be driven by a pulley 16. The pulley 16 is loose on the shaft but 75 may be operatively connected thereto by tripping a spring-controlled clutch of the usual kind contained in the hub 16^a of the pulley. These parts are all of familiar construction and need no further descrip- 80 tion.

The clutch is normally held in such a position as to prevent operative connection of the pulley 16 to the shaft 15 by means of a spring-controlled rod 17. Said rod has 85 sliding bearing in lugs 18—18 formed on a plate 19 fixed to the side of the press and a suitably mounted coiled spring 20 mounted on the rod between said lugs acts to hold said rod in an elevated position in engagement with the tripping mechanism of the clutch so as to make said clutch inoperative. 90

The safety appliance includes a right hand arm 21 and a left hand arm 22. These arms are placed on opposite sides of the press 95 and as shown herein, are mounted on the tilting body of the press. Said arms are coupled together by a horizontal, transverse, rock shaft 23 mounted in the tilting press body, back of the plane in which the plunger 100 reciprocates, and by means of a short crank arm 24. The arm 22 is fixed to the rock shaft 23. The crank arm 24 is also fixed to the shaft 23 and is pivotally connected to the right hand arm 21.

The arm 21 has a goose-neck 21^a at its 105 rear end, which is pivoted to the crank arm 24 which stands in an upright position. The arm 21 normally rests at a point intermediate its ends upon a stop 25 fixed to the side face of the swinging body of the press. This stop normally prevents the arm 21

from being moved. The arm 21 is connected to the tripping rod 17 in such manner that when the said arm 21 is depressed, it will pull down the rod 17 against the action of the spring 20. This connection consists of an arm 26 pivoted to the press body on a pin 27 located above the crank arm 24; of a link 28 which is pivotally connected to the forward end of said arm 26 and is also directly connected to the rod 17; and of a link 29 which is pivotally connected to the arm 26 at a point intermediate its ends and is pivotally connected to the arm 21 at a point forward of the goose-neck 21^a and to the rear of the stop 25. Thus, when the arm 21 is swung downwardly upon its pivotal connection with the crank arm 24, as will presently be described, it, through the link 29, swings the arm 26 downwardly which in turn pulls down the link 28 and the rod 17 against the action of the spring 20.

On the left hand side of the machine, there is associated with the arm 22 a mechanism connected with the drive shaft for positively returning the attachment to its initial position after each operation of the press. This mechanism is as follows:—a cam 30 is fixed on the shaft 15 in the vertical plane in which the arm 22 operates. 31 indicates an arm pivoted to the side of the press body to the rear of the shaft 15 at 32 and operatively engaged at its forward end 33 with the cam 30, an antifriction roller 33^a being carried at said forward end with direct engagement with the cam. 34 indicates a rod which connects the arm 31 with the arm 22. Said rod has a fork 35 at its bottom end which embraces the arm 22 and which carries a pin 36 that engages in a vertical slot 37 in the arm 22. A coiled spring 38 connecting the arm 31 to a fixed part on the frame acts to hold the anti-friction roller 33^a in positive engagement with the cam 30. The parts normally stand in the position indicated in Figs. 1, 2 and 3.

The parts are designed to act as follows:—When the press is to be started, the 50 left hand arm 22 is depressed. This is made possible by reason of the fact that the pin 36, as the parts are designed, normally stands in a position near the bottom of the slot 37 in the arm 22. The movement downward of the arm 22 rocks the shaft 23 forwardly and the crank arm 24 in the same direction so that the arm 21 is bodily moved forward, the parts being brought into the position shown in Fig. 5. The arm 21 is 55 provided on its under side with a notch 40, which is so placed in the arm that when the parts are in the position indicated in Fig. 5, after the movement above described, said notch will be in a position in line with the 60 stop 25, such that the arm 21 with its pivotal

connection with the arm 24 moved forwardly as described, may be swung downwardly without engaging the stop until it has moved far enough to pull down the arm 26 and actuate the tripping member, as 70 shown in Fig. 6. This movement trips the clutch in a familiar manner and the pulley 16 is operatively connected with the shaft. As the shaft rotates and produces a reciprocation of the press, the cam 30 rotates in 75 the direction indicated by the arrow in Figs. 3, 5, 6 and 7, and the operation is such that when the shaft 15 is approaching a complete revolution, the arm 31 begins to rise. In this movement it lifts the pin 36 80 which is now engaged with the top of the notch and thus lifts the arm 22 so that finally at the end of the revolution of the shaft, the arm 22 has been raised to its original position. In this movement the 85 rock shaft 23 is turned backwardly so as to draw the arm 21 toward the rear, thus bringing said arm again into supporting engagement with the stop as in the first position of the parts, so that the spring-controlled tripping member 17 is again returned in the path of the trip of the clutch and the pulley 16 is operatively disconnected from the shaft 15.

From the foregoing description it is apparent that the workman is unable to tie the arm 22 down and thus arrange the attachment in such manner that he can operate it with one hand. The attachment operates to actually effect the disconnection 95 of the driving pulley from the shaft after each operation, at the same time returning the parts of the attachment to their original positions, and it is thus necessary for the operator to use both hands when he desires 100 to start the press.

The many advantages of my invention will be manifest to those familiar with the art.

I claim as my invention:

1. A safety appliance of the kind described, comprising in combination with a machine, a tripping member for starting said machine, a rock shaft, a short crank arm at the 115 other end of said shaft and adapted to be operated thereby, a third arm pivotally connected with said crank arm, means connecting said third arm with said tripping member, a stop to prevent said third arm from 120 operating said tripping member, said third arm being provided with a notch which in a certain position of the parts will be in line with said stop, and means for returning said parts to their initial position after each operation of the machine.

2. A safety appliance of the kind described, comprising in combination with a machine, a spring-controlled tripping member for starting said machine, a rock shaft, 130

an arm fixed to one end of said shaft, a short crank arm fixed in an upright position to the other end of said shaft, a third arm pivotally connected to said crank arm, a stop 5 against which said third arm is normally engaged, means operatively connecting said third arm with said tripping member, said third arm being formed to permit its movement notwithstanding said stop, after said 10 first named arm has been operated to rock said shaft, and means for positively returning said parts to their initial position after each operation of the machine.

3. A safety appliance of the kind de- 15 scribed, comprising in combination with the drive shaft of a machine and the pulley and clutch thereon, a tripping member for starting said machine, a rock shaft, an arm fixed to one end of said shaft, a cam on said drive 20 shaft, means intermediate said cam and said arm for returning said arm to its initial position after it has been depressed and when the shaft has made a rotation, a short crank 25 arm fixed in an upright position at the other end of said rock shaft, a third arm pivotally connected to said crank arm, a stop adapted to normally prevent the depression of said third arm, said third arm being provided with a notch adapted to be brought 30 into alinement with said stop when said crank arm has been shifted by the operation of the first-named arm, and means operatively connecting said third arm with said tripping member.

4. A safety appliance of the kind de- 35 scribed, comprising in combination with the drive shaft of a machine and the pulley and clutch thereon, a tripping member for starting said machine, a rock shaft, an arm fixed to one end of said shaft, a cam on said drive 40 shaft, means intermediate said cam and said arm for returning said arm to its initial position after it has been depressed and when the shaft has made a rotation, a short crank 45 arm fixed in an upright position at the other end of said rock shaft, a third arm having a goose-neck pivotally connected to said crank arm, a stop adapted to normally prevent the depression of said third arm, said third arm being provided with a notch 50 adapted to be brought into alinement with said stop when said crank arm has been shifted by the operation of the first-named arm, a fourth arm pivoted above said third named arm and connected to said tripping 55 member, and a link connecting said fourth arm to said third arm at a point intermediate said notch and its connection with said crank arm.

In testimony that I claim the foregoing as 60 my invention I affix my signature in the presence of two witnesses, this 11th day of April, A. D. 1916.

THOMAS STOBS.
